UNITED STATES PATENT OFFICE.

ENOS F. SCHLICHTER, OF PHILADELPHIA, PENNSYLVANIA.

SILO.

1,147,447.

Specification of Letters Patent. Patented July 20, 1915.

Application filed April 16, 1915. Serial No. 21,809.

To all whom it may concern:

Be it known that I, ENOS F. SCHLICHTER, a citizen of the United States, residing in the city and county of Philadelphia, State of Pennsylvania, have invented a new and useful Silo, of which the following is a specification.

My invention consists of a new and useful silo top having novel means for connecting the same with the silo body.

It further consists of other novel features of construction, all as will be hereinafter fully set forth.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 is a vertical sectional view on line $x-x$ Fig. 2 of the upper portion of a silo body showing the top sections in open position. Fig. 2 is a horizontal section thereof on line $y-y$ Fig. 1. Fig. 3 is a perspective view of a hinge employed, in detached position. Fig. 4 is a sectional view on line $z-z$ Fig. 3. Fig. 5 is a sectional view on line $a-a$ Fig. 3. Fig. 6 is a top plan view of a plate employed, on an enlarged scale, with the stretchers broken away. Fig. 7 is a sectional view of the plate, showing pivotal connection of the stretchers therewith. Fig. 8 is an enlarged view showing the connection between a top section and a bolt employed.

Similar numerals of reference indicate corresponding parts in the figures.

Referring to the drawings:—1 designates the upper portion of the silo tank or body, which may be of any suitable or desired construction to accomplish the desired result, and in the present instance, is shown as of a hollow tile construction. Around the upper edge of the body or tank 1, I have provided a groove 2 for a purpose to be hereinafter described.

3 designates the top sections, preferably in the form of triangles which are hingedly connected with the top of the silo, and between the top sections are flexible sections

4 suitably connected with them and formed of canvas or other suitable material, the flexible sections serving to close the spaces between the top sections when the latter are open or unfolded. In order to movably connect the top sections with the top of the body, I have provided a suitable number of hinges depending upon the number of top sections employed. As each of the hinges 60 are of similar construction, I will describe one.

5 designates a bracket forming a base and which is adapted for suitable connection with the body of the silo. As here shown, I have provided the downwardly extending members 6, through which pass the clamping members, such as set screws 7, in order that the bracket 5 can be firmly connected with the top of the silo and removed 65 therefrom. The upper face 8 of the bracket serves as a track or guide and is provided with the longitudinally extending slot 9.

10 designates a bed slidably mounted upon the bracket 5 in order to be adjustable thereon and carries the clamping means 11 for locking the bed in its adjusted positions. The bed 10 carries a laterally extending arm 12 having longitudinally extending slots 13 therein and provided with the depending 75 side wings 14, the ends of which are adapted, when the hinge is in position on the body 1, to be located in the groove 2 to assist in holding the parts in position.

15 designates bolts seated in said slots 13 and which are provided with the clamping means 16, here shown as nuts and washers, for locking the same to the arm 12, it being understood that the said bolts can be moved in the slots 13 laterally of the bracket, independently of each other, and locked in their 80 adjusted positions. I have also provided means for longitudinal adjustment of the bolts 15 with respect to the bracket 5, and in the present instance I have shown the 85 same as provided with threads 17, engaging the locking means or nuts 16, for this purpose. Each of the bolts is provided with an eye 18 adapted to receive a pintle or other suitable means for pivotally connect- 90

ing the same with the top sections. As here shown, I have provided the top sections 3 with the inwardly extending flanges 19, and I so locate the bracket 5 in order that one bolt 15 will be connected with one top section and the other bolt 15 thereof will be suitably connected with the next adjacent 95 100 105 110

top section. By this means, each top section will be hingedly connected at its opposite side with the body, thus insuring a strong and durable structure and the proper 5 operation of the raising and lowering of the top sections, as will be evident.

I have found in practice, in the construction of silos, particularly of the hollow tile construction, that the same are never true to 10 a circle. This arises from the fact that in the manufacture of the hollow tiles, there is always a slight variation in the tiles themselves, due to the burning, and also during the setting up of the same, it is impossible 15 to have the same amount of material, such as cement, inserted between the joints for connecting the parts. These reasons will, in some instances, cause a variation in the diameter of a number of inches and will 20 throw the body out of the true circle. The top sections are manufactured for a given size of tank, say twelve feet. A silo which is constructed with the idea of being a twelve foot silo will vary a number of 25 inches, that is to say, one diameter might be, for example, eleven feet ten inches, and a cross sectional diameter at right angles thereto might be twelve feet two inches. Due to this variation, it is essential to have 30 some means for suitably connecting the top sections to the body to insure that they will properly open and close. By means of my novel hinge just described, it will be evident that I can independently adjust, both 35 laterally and longitudinally, each of the bolts 15 on the body, in order that the eyes thereof, that is the points of connection, can be properly located to be suitably connected with adjacent top sections, in order 40 that the hinge of the top sections of the body will be located to cause the sections to close with respect to each other. In addition, an initial adjustment of the body on the bracket can be made, in order that the 45 ends of the depending arms 14 will properly enter the groove 2 in the top edge to assist in holding the parts in position. I have also shown a structure by means of which I can open and close the top sections. 50 Adjacent the upper portion of each of the top sections 3, I pivotally connect the outer end of a stretcher 20, the opposite end of each of which is pivotally connected at 21 with a plate 22, which is carried by a sleeve 55 23. Extending forwardly or outwardly from the plate are pairs of lugs 24 having alining openings and between each pair of lugs a stretcher is adapted to be situated when the top sections are in opened position. 60 A suitable member of said stretchers are provided with an opening 25 adapted, when in alinement with the openings in the lugs 24, for the reception of a locking means, such as the pin 26, which also passes through 65 the openings in the lugs 24 in order to lock

the stretchers to hold the top sections in opened position. I have illustrated the locking means as cotter pins carried by chains 27, one end of which is suitably connected with the plate 22.

70

28 designates a cap, preferably conical, carried by a rod 29, which is movable in the sleeve 23 and may be held in different positions therein by a set screw 30. When the parts are in the position seen in Fig. 1, by 75 releasing or removing the pins 26 from their engagement with the stretchers 20, the plate can be lowered or drawn down, thus swinging the top sections 3 upon their hinges to cause them to assume the position seen in 80 dotted lines in Fig. 1 and closing the top, after which the cap 28 can be lowered on the sleeve 23 to a position above the ends of the top sections, and can then be locked in this position, if desired. When it is desired to 85 open the top, the cap 28 is first pushed upwardly to permit outward movement of the 90 ends of the top sections, after which the plate 22 is elevated, forcing outwardly the free ends of the top sections until the openings in the stretchers 20 aline with the openings of the lugs 24, when the pins 26 can be again inserted to lock the parts in their opened position.

95

It will now be apparent that I have devised a novel and useful silo, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from 105 the spirit or scope of the invention or sacrificing any of its advantages.

100

Having thus described my invention, what I claim as new and desire to secure by Letters Patent, is:—

110

1. In a silo, the combination of a tank having top sections adapted to be hinged to the upper end thereof to close together to form a top with a plurality of hinges each comprising a base connected to the top of the tank, a bed slideable on said base, and a bolt laterally and longitudinally adjustable on the bed and pivotally connected with a top section.

115

2. In a silo, the combination of a tank having top sections adapted to be hinged to the upper end thereof to close together to form a top with a plurality of hinges each comprising a base connected with the top of the tank, a bed slideable on said base, a bolt laterally and longitudinally adjustable on the bed and pivotally connected with a top section, and means for locking the bolt in its adjusted position.

120

3. In a silo, the combination of a tank

125

130

having top sections adapted to be hinged to the upper end thereof to close together to form a top with a plurality of hinges each comprising a base connected to the top 5 of the tank, a bed slideable on said base, a pair of bolts independently and laterally adjustable on the bed, one being pivotally connected with one top section and the other with the next adjacent top section, and independent means for locking the bolts in 10 their adjusted positions.

4. In a silo, a tank, top sections adapted to be hinged to the upper end of said tank to close together to form a top, a pair of 15 bolts each connected with adjacent top sections, a slidingly supported bed for each pair of bolts, means for independently adjusting and locking each bolt on the bed, and a base for each bed connected with the 20 tank and upon which the bed is movable and adjustable.

5. In a silo, the combination of a tank having a groove in the upper face and provided with top sections adapted to be hinged 25 to the upper end thereof to close together to form a top with a plurality of hinges each comprising a base connected to the top of the tank, a bed slideable on said base and having arms adapted to be seated in the 30 groove, a bolt laterally and longitudinally adjustable on the bed and pivotally connected with a top section, and means for locking the bolt in its adjusted position.

6. A hinge for a silo top comprising a 35 base having means for clamping the same to the silo tank, a bed longitudinally slideable on the base, means for locking the base in adjusted position, and bolts carried by said bed independently adjustable laterally 40 and longitudinally and adapted for connection with top sections of the silo.

7. A hinge for a silo top comprising a base having means for clamping the same to the silo tank, a bed longitudinally slideable 45 on the base, means for locking the bed in adjusted position, bolts carried by said bed independently adjustable laterally and longitudinally thereon and adapted for connection with top sections of a silo, and 50 means for each bolt for locking the same in adjusted position.

8. A hinge for a silo top comprising a base having means for clamping the same to the silo tank, a bed longitudinally slideable 55 on said base and having laterally ex-

tending slots therein, means for locking the bed in adjusted position, a bolt in each slot laterally adjustable therein and adapted for connection with a top section of the silo, and locking means for said bolts in which 60 they are longitudinally adjustable.

9. A hinge for a silo top comprising a base having means for clamping the same to the silo tank, a bed longitudinally slideable on the base, arms on said bed depending therefrom to a point beneath the bottom wall of the base, means for locking the bed in adjusted position, and bolts carried by said bed independently adjustable laterally and longitudinally and adapted for connection 70 with adjacent top sections of the silo.

10. A hinge for a silo top comprising a base having means for clamping the same to the silo tank, a bed longitudinally slideable on the base and having laterally extending slots therein, arms on said bed extending downwardly on opposite sides thereof below the bottom wall of said base, means for locking the bed in adjusted positions, a bolt in each slot laterally adjustable therein 75 and adapted for connection with adjacent top sections of the silo, and locking means for said bolts in which they are longitudinally adjustable.

11. In a silo, the combination of a body, 85 top sections hinged to said body, stretchers pivotally connected at one end to a top section, a plate to which the opposite end of each stretcher is pivoted, and means for locking the stretchers to the plate for holding the sections in opened position.

12. In a silo, the combination of a body, top sections hinged to said body, stretchers pivotally connected at one end to a top section, a plate to which the opposite end of 95 each stretcher is pivoted, ears projecting from the plate adjacent each stretcher, and means for locking the stretchers to the ears for holding the sections in opened position.

13. A hinge for a silo top comprising a 100 base having means for clamping the same to the silo tank, a bed slideable on the base, means for locking the bed in adjusted positions and means carried by the bed adjustable laterally and longitudinally thereon for 105 connection with a top section of the silo.
